UNITED STATES PATENT OFFICE.

FRANK P. DAUGHADAY, OF NORTON, MASSACHUSETTS.

DESIGN FOR A BUCKLE.

Application filed May 5, 1927. Serial No. 21,861. Term of patent 3½ years.

To all whom it may concern:

Be it known that I, FRANK P. DAUGHADAY, a citizen of the United States, residing at Norton, in the county of Bristol and State of Massachusetts, have invented a new, original, and ornamental Design for Buckles, of which the following is a specification, reference being had to the accompanying drawing, forming part thereof.

Figure 1 is a plan view of the buckle showing my new design, the frame being

shown in solid lines and the tongue being partially shown by dotted lines, it being understood that the tip of the tongue has not been completed in order to avoid obscuring the ornamentation displayed on the buckle frame.

Figure 2 is an edge view of the buckle.

I claim:

The ornamental design for a buckle, as shown and described.

FRANK P. DAUGHADAY.
